DESIGN FOR A TRAILER

Frederick C. Hoffman, Los Angeles, Calif.

Application August 14, 1946, Serial No. 132,522

Term of patent 7 years

(Cl. D14—3)

To all whom it may concern:

Be it known that I, Frederick C. Hoffman, a citizen of the United States, residing in Los Angeles, in the county of Los Angeles and State of California, have invented a new, original, and ornamental Design for a Trailer, of which the following is a specification, reference being had to the accompanying drawing, forming part thereof.

Fig. 1 is a perspective view of a trailer, showing my new design.

Fig. 2 is a side elevational view.

Fig. 3 is a rear elevational view.

Fig. 4 is a front elevational view.

The dominant features of the design are embodied in the parts shown in full lines.

The opposite side to that shown in Fig. 2 is the same as shown in Fig. 2, except for the door,

and except for the fact that the longitudinal ribs along the lower portion of the body are continuous from the front end to the rear end of the trailer, on said opposite side.

I claim:

The ornamental design for a trailer, substantially as shown and described.

FREDERICK C. HOFFMAN.
